ELECTRICAL SWITCH

Charles Adin Fox, Oakland Village, Mo., assignor
to James R. Kearney Corporation, St. Louis,
Mo., a corporation of Missouri

Application March 8, 1943, Serial No. 478,337

8 Claims. (Cl. 200—162)

This invention relates generally to electrical switches and more specifically to electrical switches of the manually-operated, disconnect type, the predominant object of the invention being to provide an electrical switch of this type which is of such improved construction and arrangement that the mechanical structure of the switch is simplified and improved and which, because of its improved construction, is capable of performing its intended function in an improved and highly efficient manner.

Prior to this invention many disconnect switches of the general type to which the present invention relates, included in their mechanical structures contacts which were made up largely of castings, and the presence of these castings added to the weight and complexity of the switches referred to and increased the cost of manufacture thereof because of the initial cost of the castings and the expense incident to machining and otherwise preparing said castings for use. The predominant feature of the switch of the present invention resides in the fact that the improved switch includes contacts which are produced largely from sections of relatively heavy, resilient wire material or rod material, which may be conveniently and economically produced, thereby eliminating the castings heretofore required in providing the contacts of earlier switches of the general type to which the present invention relates and doing away with the disadvantages attached to the use of such castings.

Fig. 1 is a side elevation of the improved switch, a portion of the blade thereof being shown in section.

Fig. 2 is a front elevation of the switch shown in Fig. 1.

Fig. 3 is a plan view of the switch illustrated in Figs. 1 and 2, a portion of the supporting member of the switch being shown in section.

Fig. 4 is a fragmentary, horizontal section taken on line 4—4 of Fig. 2 and looking in the direction indicated by the arrows.

Fig. 5 is a fragmentary, rear elevation illustrating one of the connectors employed for connecting the incoming and outgoing electrical conductors to the improved switch.

In the drawings, wherein is shown for the purpose of illustration, merely, one embodiment of the invention, A designates the improved switch generally. The switch A, as illustrated in the drawings, includes a supporting member 1 which, as shown to the best advantage in Fig. 3, may be of channel formation, said supporting member

1 having fixed thereto a pair of spaced, outstanding insulators 2 and 3 of suitable construction. The insulators 2 and 3 may be secured to the supporting member 1 in various ways, one such being to provide each insulator with a fixedly attached end member 4 from which a screw-threaded shank 5 extends, said shank being projected through an opening 6 (Fig. 3) formed through the forward wall of the supporting member 1 and having a nut 7 mounted thereon which secures the end member and insulator assembly to the supporting member. The openings 6 formed in the forward wall of the supporting member 1 through which the screw threaded shanks 5 extend, are preferably elongated vertically and extensions 8, formed on the end members 4 of the insulators 2 and 3, project into said openings so as to prevent rotation of the insulators about the axes of the screwthreaded shanks 5 of said insulators.

Secured to the insulator 3 is the lower contact 9 of the switch A, and secured to the insulator 2 is the upper contact 10 of the switch. The lower contact 9 includes as a part thereof the contact part 11, which is shown to good advantage in Figs. 1, 2, and 4, said contact part being formed from a length of flat metal, or other suitable material, that is of considerable height as shown in Fig. 1, and is of substantially U-shaped formation as shown in Fig. 4. The base 11a of the contact part 11 is disposed in spaced relation with respect to the outer face of the insulator 3, and an aperture 11b is formed through said base substantially centrally thereof. The spaced arms 11c of the contact part 11 extend forwardly from the opposite ends of the base of said contact part in substantial parallelism, said spaced arms being provided with notches 12 at their forward ends which are open at the forward ends of the arms and are closed at their rear ends and at their tops and bottoms by wall portions of said notches (see Fig. 1). The spaced arms 11c of the contact part 11 are provided with aligned apertures 13 formed therethrough which serve a purpose to be hereinafter set forth.

The lower contact 9 includes also a member 14, in the form of a U-shaped length of rod material, which contacts with an end member 15 that is in the form of a cap and is suitably fixed to the insulator 3 at the forward end thereof, said U-shaped member 14 comprising a pair of spaced, vertically extended portions which are joined at their lower ends by a bridge portion (see Fig. 2). Arranged in contact with forward portions of the spaced, vertical portions of the mem-

ber 14 is a plurality of contact elements 16, each of which is formed of resilient rod material and is shaped in plan as shown in Fig. 4. In other words, each of the contact elements 16 includes a rear portion 16a which is disposed horizontally and portions of which contact with the spaced, vertical portions of the member 14, opposed and slightly convergent portions 16b which extend forwardly from the opposite ends of said rear portion 16a, and rounded forward portions 16c at the forward ends of said portions 16b which are provided with parallel, rearwardly extended and spaced apart extensions 16d.

As is shown to good advantage in Figs. 1 and 2, the contact elements 16 are arranged in pairs, there being an upper pair and a lower pair of said contact elements and these pairs of contact elements are spaced apart vertically. Also, the extensions 16d of the respective contact elements 16 are spaced inwardly from the convergent portions 16b of the corresponding contact elements, as shown in Fig. 4, and the forward portions of the spaced arms 11c of the contact part 11 are disposed between the extensions 16d and the convergent portions 16b of said contact elements, with the rounded portions 16c of said contact elements located in the notches 12 of said spaced arms of said contact part 11. Because of this arrangement the upper pair of contact elements 16 and the lower pair of contact elements 16 are respectively prevented from moving upwardly and downwardly to an excessive degree at their forward ends, inasmuch as the upper and lower walls of the notches 12 of the spaced arms of the contact part 11 will arrest such movement before it becomes excessive.

Forming a part of the lower contact 9 of the switch A is a vertically disposed member 17 which is preferably of channel formation, as shown in Fig. 4. The channel member 17 is interposed between the base portion 11a of the contact part 11 and the rear portions 16a of the contact elements 16, said base 11a of the contact part 11 contacting with the forward wall of the channel member 17 while the rear edges of the spaced side walls of the channel member contact with the rear portions of the contact elements 16. It will be noted by referring to Fig. 4 that the spacing of the spaced, vertical portions of the U-shaped member 14 is greater than the width of the channel member 17, and as a result of this situation the points at which the rear edges of the spaced walls of said channel member contact with the rear portions of the contact elements 16 are located inwardly of the points where said rear portions of said contact elements 16 contact with said spaced, vertical portions of said U-shaped member 14. This arrangement is important for a reason to be hereinafter referred to.

In order to secure the various parts of the lower contact 9 in an assembled condition to the insulator 3, the end member 15 of said insulator 3 has fixed thereto and extended outwardly therefrom a screwthreaded shank 18. This shank passes between the spaced, vertical portions of the U-shaped member 14, between the rear portions of the vertically spaced pairs of contact elements 16, and said shank extends through an opening 11a of the channel member 17 and through the opening 11b formed through the base of the contact part 11. Mounted on the outer portion of the screwthreaded shank 18 is a nut 19 which contacts forcibly with a washer assembly 20 to force the contacting portions of the various parts of the lower contact 9 into close gripping

contact to securely fix the lower contact to the insulator 3. In this connection it is pointed out that when the nut 19 is drawn up hard on the screwthreaded shank 18 the rear portions of the contact elements 16 are bowed rearwardly slightly between the locations of the spaced vertical portions of the U-shaped member 14. This produces spring contact between said rear portions of said contact elements 16 and said spaced vertical portions of the U-shaped member 14 which will maintain close contact between said portions even though the nut 19 should become unintendedly loosened slightly. Additionally, the action of drawing the nut 19 up tight on the screwthreaded shank 18 will produce an embedding action, where the rear portions of the contact elements 16 contact with the spaced, vertical portions of the U-shaped member 14, with the result that these portions are interlocked to further improve the attachment of said parts and the securing of the lower contact to the insulator 3.

The switch A includes, also, a switch blade 21 which preferably, though not necessarily, is in the form of a tube formed from electrical conducting material. Adjacent to its lower end the switch blade 21 is provided with opposed apertures in which is supported a transversely extended pin 22, said pin being of such length that it extends outwardly beyond opposite sides of the switch blade 21 to provide opposed trunnions that are mounted for rotation in the openings 13 formed in the spaced arms 11c of the contact part 11. This arrangement provides for pivotal support of the switch blade relative to the lower contact in order that its upper portion may be swung into and out of closed-switch position with respect to the upper contact 10 of the switch. The pin 22 may be secured to the switch blade 21 in various ways, one such being to provide the pin with slightly raised, knurled portions 22' and drive these knurled portions into the walls of the aligned apertures of the switch blade. According to this arrangement, the leading knurled portion of the pin, as said pin is passed through the switch blade 21 is of slightly less height than the trailing knurled portion of the pin in order that it will pass through the first opening of the switch blade through which the leading portion of the pin passes. The switch blade 21 is provided with a pin 23 which serves to expedite the action of engaging a switch stick with the switch blade when said switch blade is to be moved to the closed-switch or open-switch positions. The pin 23 may be secured to the switch blade in the same manner in which the pin 22 is secured thereto, as described above.

The upper contact 10 of the switch A includes a member 24 which is shaped as shown to good advantage in Figs. 1 and 3. The member 24 is formed from a single length of heavy wire material or rod material and it includes spaced, vertical portions 25 which are arranged in engagement with the outer face of an end member 26 that is suitably fixed to the upper insulator 2. Extended forwardly from the lower ends of the vertical portions 25 of the member 24 is a pair of spaced portions 27 which are joined at their forward ends by a portion 28 which, as shown in Fig. 3, is preferably bowed slightly in a rearward direction. The portion 28 serves as a stop to limit rearward movement of the upper portion of the switch blade when said switch blade is moved into contact with the upper contact 10 as will be presently described herein.

The upper contact 10 includes also a plurality

of contact elements 29 which are arranged in spaced pairs and are shaped in accordance with the contact elements 16 of the lower contact 9; that is to say, each of the contact elements 29 includes a rear portion 30, a pair of opposed and slightly convergent portions 31, rounded outer portions 31' and rearwardly extended, spaced portions 32. The rear portions 30 of the contact elements 29 engage the vertical portions 25 of the member 24 so that said vertical portions 25 are interposed between said rear portions 30 of the contact elements 29 and the forward face of the end member 26 of the upper insulator 2.

In order to secure the member 24 and the elements 29 of the upper contact 10 to the insulator 2 a member 33 is provided which resembles the member 17 of the lower contact 9, in that said member is preferably of channel formation and is provided with an aperture formed through its forward wall through which is extended a screw-threaded shank 34 that is fixed to and extends forwardly from the end member 26 of the insulator 2. The rear edges of the side walls of the member 33 contact with the rear portions 30 of the contact elements 29, as shown in Fig. 3, and a nut 35 is mounted on the screwthreaded shank 34 which may be drawn up on said screwthreaded shank to force the member 33, rearwardly and thereby force the rear portions 30 of the contact elements 29 into close contact with the vertical portions 25 of the member 24 and in turn force said vertical portions 25 into close contact with the forward face of the end member 26 of the insulator 2. As in the case of the lower contact 9, as previously explained, the action of drawing up the nut 35 on the screwthreaded shank 34 of the upper contact, bows the rear portions 30 of the contact elements 29 slightly in a rearward direction with the result that spring contact is produced between the resilient rear portions of the contact elements 29 and the vertical portions 25 of the member 24, and as a result of this spring contact close contact between said parts will be maintained even though the nut 35 becomes unintentionally loosened slightly. Also, an interlocking action is obtained between the rear portions 30 of the contact elements 29 and the vertical portions 25 of the member 24, due to said portions being embedded in each other at the point where they contact, because of the clamping force exerted by the nut 35.

The members 33 and 17 constitute the incoming and outgoing terminals of the switch A to which the incoming and outgoing electrical conductors C_a and C_b are connected, and each of said members has associated therewith a connector 36, said connectors being of like construction and arrangement. Each connector 36 includes a U-shaped body portion 37 which is of such rectangular formation and of such dimensions that it fits between the opposed side walls of the associated channel-shaped member 17 or 33 and contacts with the inner face of the forward wall thereof. Associated with the body portion 37 of each connector 36 is a clamping element 38 which comprises a shank portion 39, screwthreaded at its outer end portion, and an eye portion 40 at the opposite end of said shank portion. The shank portion 39 of the clamping element 38 extends through an opening formed through the portion of the body portion 37 which produces the base thereof and through an alined opening formed through the forward wall of the associated member 17 or 33, there being a nut 75

41 mounted on the screwthreaded part of the shank portion of the clamping element of each connector which is adapted to engage the outer face of the associated member 17 or 33. The spaced side walls of the body portion of each connector are provided with alined conductor seats 42 which are adapted to receive a conductor engaged by the connector.

When a conductor is to be engaged by one of the connectors 36 the nut 41 thereof is unscrewed to permit the clamping element 38 to move outwardly relative to the body portion 37 a sufficient distance to allow the conductor to be passed through the eye of said clamping member and between the inner wall thereof and the conductor seats 42. The nut 41 is then tightened to draw the eye portion of the clamping element 38 inwardly of the body portion 37 so as to securely clamp the conductor between the inner wall of the eye portion of the clamping element and the conductor seats 42 of the opposed walls of said body portion 37. In addition to clamping the conductor as described, the action of tightening the nut 41 serves to securely clamp the body portion of the connector to the associated member 17 or 33, as the inward movement of the clamping element transmits movement through the clamped conductor to the body portion 37 which forces the base of said body portion into close contact with the associated member whereby the forward wall of said associated member is firmly clamped between said base of said body portion and the nut 41. Conductors may be clamped by the connectors 36 when said conductors extend longitudinally of the associated members 17 or 33, as is shown in Fig. 1 and by full lines in Fig. 7. Also, the connector may be shifted about the axis of the shank portion of its clamping element one-quarter of a revolution to bring the connector to a position relative to the associated member 17 or 33 where a conductor which extends transversely of said associated member may be engaged thereby, as shown by dotted lines in Fig. 7.

In the use of the improved switch disclosed herein the switch blade 21 may be moved into or out of engagement with the upper contact 10 by engaging the switch blade with a suitable switch stick at the location of the pin 23 and moving the switch blade to the desired position. It is to be noted that when the switch blade is in the closed switch position the opposite end portions of said switch blade are closely engaged by the portions 16d of the resilient contact elements 16 of the lower contact 9 and by the portions 32 of the resilient contact elements 29 of the upper contact 10 to provide flexible, floating, point pressure contact between said contact elements and said switch blade to afford the desired and required good electrical contact between said parts. Also, because the contact elements 16 of the lower contact 9 are arranged in spaced pairs, the switch blade is arrested, and may be retained, in a horizontal position when said switch blade is in the open switch position, this result being brought about because the portions 16d of the resilient contact elements 16 will move inwardly, when the switch blade is in the horizontal position, to engage receding portions of the surface of the switch blade located above and below the point of pivotal connection of the switch blade. Additionally, because of the fact that portions of the contact elements 16 of the lower contact are disposed in the notches 12 of the contact part 11 of said lower contact, undue spreading of the outer end portions of the pairs

of contact elements is prevented when the switch blade is in the horizontal position, or at any other time.

I claim:

1. A contact for an electrical switch having supporting means for supporting the contact, comprising a member having spaced extensions which contact with a face of said supporting means, a plurality of contact elements formed from lengths of resilient material which are provided with portions that contact with the spaced extensions of said member, and means for securing said member having spaced extensions and said plurality of contact elements to said supporting means, said securing means comprising a member which contacts with said portions of said plurality of contact elements at points thereof located inwardly of said spaced extensions of the first-mentioned member, and means for moving the second-mentioned member so as to force said portions of said plurality of contact elements into close contact with said spaced extensions of said first-mentioned member and for forcing said spaced extensions of said first-mentioned member against the face of the supporting means with which they contact.

2. A contact for an electrical switch having supporting means for supporting the contact, comprising a member having spaced extensions which contact with a face of said supporting means, a plurality of contact elements formed from lengths of resilient material which are provided with portions that contact with the spaced extensions of said member, and means for securing said member having spaced extensions and said plurality of contact elements to said supporting means, said securing means comprising a member which contacts with said portions of said plurality of contact elements at points thereof located inwardly of said spaced extensions of the first-mentioned member, and means comprising a screwthreaded shank supported by said supporting means and a nut mounted on said screwthreaded shank for moving the second-mentioned member so as to force said portions of said plurality of contact elements into close contact with said spaced extensions of said first-mentioned member and for forcing said spaced extensions of said first-mentioned member against the face of the supporting means with which they contact.

3. A contact for an electrical switch having supporting means for supporting the contact, comprising a member having spaced extensions which contact with a face of said supporting means, a plurality of contact elements formed from lengths of resilient material which are provided with portions that contact with the spaced extensions of said member, and means for securing said member having spaced extensions and said plurality of contact elements to said supporting means, said securing means comprising a channel member which contacts with said portions of said plurality of contact elements at points thereof located inwardly of said spaced extensions of the first-mentioned member, and means for moving said channel member so as to force said portions of said plurality of contact elements into close contact with said spaced extensions of said first-mentioned member and for forcing said spaced extensions of said first-mentioned member against the face of the supporting means with which they contact.

4. An electrical switch comprising spaced contacts, supporting means for said spaced contacts,

and a switch blade having pivot means associated therewith providing for pivotal attachment of said switch blade to one of said spaced contacts at a point adjacent to an end of the switch blade so that the opposite end portion of the switch blade may move into and out of electrical contact with the other of said spaced contacts, said contact to which the switch blade is pivotally attached including elongated spaced arms which are supported by and extend from the supporting means for the contact, a portion of the switch blade being disposed between said spaced arms in spaced relation with respect thereto and said spaced arms being provided with apertures which receive portions of said pivot means, and a plurality of contact elements formed from lengths of resilient material, said contact elements being supported by the supporting means for the contact and being composed of opposed portions extended forwardly from said contact-supporting means in outwardly spaced relation with respect to the outer faces of said spaced arms and with respect to the switch blade, and inwardly and rearwardly bent forward portions disposed in inwardly spaced relation with respect to the inner faces of said spaced arms and which contact with opposite outer portions of said switch blade to make good electrical contact therewith, forward portions of said contact elements being arranged in embracing relation with respect to forward portions of said spaced arms.

5. An electrical switch comprising spaced contacts, supporting means for said spaced contacts, and a switch blade having pivot means associated therewith providing for pivotal attachment of said switch blade to one of said spaced contacts at a point adjacent to an end of the switch blade so that the opposite end portion of the switch blade may move into and out of electrical contact with the other of said spaced contacts, said contact to which the switch blade is pivotally attached including a member supported by the supporting means for the contact which is provided with elongated spaced arms that project from said contact-supporting means, a portion of the switch blade being disposed between said spaced arms in spaced relation with respect thereto and said spaced arms being provided with apertures which receive portions of said pivot means, and a plurality of contact elements formed from lengths of resilient material, said contact elements being supported by the supporting means for the contact and being composed of opposed portions extended forwardly from said contact-supporting means in outwardly spaced relation with respect to the outer faces of said spaced arms and with respect to the switch blade, and inwardly and rearwardly bent forward portions disposed in inwardly spaced relation with respect to the inner faces of said spaced arms and which contact with opposite outer portions of said switch blade to make good electrical contact therewith, forward portions of said contact elements being arranged in embracing relation with respect to forward portions of said spaced arms.

6. An electrical switch comprising spaced contacts, supporting means for said spaced contacts, and a switch blade having pivot means associated therewith providing for pivotal attachment of said switch blade to one of said spaced contacts at a point adjacent to an end of the switch blade so that the opposite end portion of the switch blade may move into and out of electrical contact with the other of said spaced contacts, said

contact to which the switch blade is pivotally attached including a substantially U-shaped member supported by the supporting means for the contact which is provided with elongated spaced arms that project from said contact-supporting means, a portion of the switch blade being disposed between said spaced arms in spaced relation with respect thereto and said spaced arms being provided with apertures which receive portions of said pivot means, and a plurality of contact elements formed from lengths of resilient material, said contact elements being supported by the supporting means for the contact and being composed of opposed portions extended forwardly from said contact-supporting means in outwardly spaced relation with respect to the outer faces of said spaced arms and with respect to the switch blade, and inwardly and rearwardly bent forward portions disposed in inwardly spaced relation with respect to the inner faces of said spaced arms and which contact with opposite outer portions of said switch blade to make good electrical contact therewith, forward portions of said contact elements being arranged in embracing relation with respect to forward portions of said spaced arms.

7. An electrical switch comprising spaced contacts, supporting means for said spaced contacts, and a switch blade having pivot means associated therewith providing for pivotal attachment of said switch blade to one of said spaced contacts at a point adjacent to an end of the switch blade so that the opposite end portion of the switch blade may move into and out of electrical contact with the other of said spaced contacts, said contact to which the switch blade is pivotally attached including a member supported by the supporting means for the contact which is provided with elongated spaced arms that project from said contact-supporting means, a portion of the switch blade being disposed between said spaced arms in spaced relation with respect thereto and said spaced arms being provided with apertures which receive portions of said pivot means, and a plurality of contact elements formed from lengths of resilient material, said contact elements being supported by the supporting means for the contact and being composed of opposed portions extended forwardly from said contact-supporting means at opposite sides of said pivot means and

- in outwardly spaced relation with respect to the outer faces of said spaced arms and with respect to the switch blade, and inwardly and rearwardly bent forward portions disposed in inwardly spaced relation with respect to the inner faces of said spaced arms and which contact with opposite outer portions of said switch blade to make good electrical contact therewith, forward portions of said contact elements being arranged in embracing relation with respect to forward portions of said spaced arms.
- 5 8. An electrical switch comprising spaced contacts, supporting means for said spaced contacts, and a switch blade having pivot means associated therewith providing for pivotal attachment of said switch blade to one of said spaced contacts at a point adjacent to an end of the switch blade so that the opposite end portion of the switch blade may move into and out of electrical contact with the other of said spaced contacts, said contact to which the switch blade is pivotally attached including a member supported by the supporting means for the contact which is provided with elongated spaced arms that project from said contact-supporting means, a portion of the switch blade being disposed between said spaced arms in spaced relation with respect thereto and said spaced arms being provided with apertures which receive portions of said pivot means, and a plurality of contact elements formed from lengths of resilient material, said contact elements being supported by the supporting means for the contact and being composed of opposed portions extended forwardly from said contact-supporting means in outwardly spaced relation with respect to the outer faces of said spaced arms and with respect to the switch blade, and inwardly and rearwardly bent forward portions disposed in inwardly spaced relation with respect to the inner faces of said spaced arms and which contact with opposite outer portions of said switch blade to make good electrical contact therewith, forward portions of said contact elements being arranged in embracing relation with respect to forward portions of said spaced arms.
